CLAIM

We claim the ornamental design for an infrared blaster, as shown and described.

DESCRIPTION

FIG. 1 is a perspective view showing the new design; FIG. 2 is a top plan view thereof; FIG. 3 is a left side elevational view thereof; FIG. 4 is a front elevational view thereof; FIG. 5 is a right side elevational view thereof; FIG. 6 is a back elevational view thereof; and, FIG. 7 is a bottom plan view thereof.

(Continued)

The broken lines showing portions of the infrared blaster in FIG. 7 are for illustrative purposes only, and form no part of the claimed design.

1 Claim, 4 Drawing Sheets
